UNITED STATES PATENT OFFICE.

JOHN T. QUINN, OF STOCKTON, CALIFORNIA, ASSIGNOR TO H. B. ALGER, OF LAKEVIEW, OREGON.

PARACHUTE-GUN.

1,102,166.

Specification of Letters Patent. Patented June 30, 1914.

Application filed February 10, 1913, Serial No. 747,354. Renewed June 1, 1914. Serial No. 842,233.

To all whom it may concern:

Be it known that I, JOHN T. QUINN, a citizen of the United States, residing at Stockton, in the county of San Joaquin and 5 State of California, have invented new and useful Improvements in Parachute-Guns, of which the following is a specification.

My invention is that of a toy, which I term a parachute gun, it comprising a gun 10 by means of which a closed parachute can be propelled upward in the air, which parachute will, on descending, open, and support therefrom the miniature image of a man on a trapeze.

15 In the accompanying drawing, Figure 1 is a perspective view, partly broken away, of my improved parachute gun before being discharged; Fig. 2 is a side view of the parachute after it has commenced to descend.

20 Referring to the drawing, 1 indicates the stock of a toy gun, to the outer end of which is transversely secured a strong bow spring 2, to the outer ends of which are secured 25 ends of strong rubber bands 3, to the other ends of which bands is secured a cord 4, which can slide in slots 5 between the upper side of said stock and a barrel 6, secured at its ends only to said stock and spaced therefrom in the central portion to form said 30 slots 5. In the rear portions of said slots 5 are formed notches 7, in which, the cord 4 can be retained if drawn rearwardly to the full extent. Said barrel is in general, of a semi-cylindrical form, and said stock is 35 formed in its upper surface with a semi-cylindrical longitudinal groove, forming with the barrel a substantially cylindrical bore 8, in which a cylindrical projectile is guided and directed when the gun is 40 charged. Said projectile comprises a cylindrical tube 9 of a diameter such that it fits properly within the cylindrical bore of the barrel, one end 11 of said tube being permanently closed. From the closed end extends 45 outside the tube and along its axis a stem 12 of a parachute 13 which, when collapsed, can fit within the bore of the gun. Said 50 parachute is formed of paper 14 or other light material supported by light bamboo strips 15, which from their resiliency tend

to expand slightly when released from the bore of the gun, so that the parachute on descending can encounter initial resistance of the air and expand. The upper ends of said strips are loosely connected to the 55 upper end of the stem 12 and their lower ends are connected by cords 16 to a collar 17 on said stem, so as to limit the extent of opening of the parachute. From said closed end hang cords 20, from the 60 lower ends of which hangs a transverse bar 21 or trapeze to which is attached by the hands the miniature image 22 of a man. Said image is made of heavy material, as iron, and to its feet is attached a closure 23 65 for the open end of the tube. The cord is drawn until it engages the notches, and the image is inclosed within the tube, and the parachute and tube are pushed into the bore of the gun, in front of the notches, the 70 parachute and tube are projected thereby from the gun. As soon as the parachute ceases to rise, said image drops and hangs from the parachute, which will then open and allow the image to slowly descend. 75

I claim:

1. In a toy, a tube of size to fit within the barrel of a gun, a stem one end of which extends axially from one end of said tube, a 80 parachute secured to the other end of the stem, said parachute when collapsed being of size to fit within said barrel, an image of heavy material within said tube, and means contained within the tube for suspending said image below said tube. 85

2. In a toy, a tube of size to fit within the barrel of a gun, a stem one end of which extends axially from one end thereof, a 90 parachute secured to the other end of the stem, said parachute when collapsed being of size to fit within said barrel, a bar within said tube, but extensible therefrom, and an image of a man suspended from said bar. 95

In testimony whereof I have hereunto set my hand in the presence of two subscribing 98 witnesses.

JOHN T. QUINN.
